Application November 16, 1950, Serial No. 196,069

2 Claims. (Cl. 198—213)

1

This invention relates to a material-handling machine and more particularly to an improved screw conveyor assembly.

The embodiment of the invention disclosed herein is particularly adapted for use in portable elevators of the type used on farms, for example, for the elevating of small grain and similar material. A typical elevator of this character comprises a mobile base, normally including a wheeled axle, from which a support extends upwardly to carry a screw conveyor assembly that inclines upwardly from a lower material-receiving end to an elevated material-discharge end. The base structure normally includes a source of power, such as an internal combustion engine or electric motor, and appropriate means is provided for rotating the auger or screw of the conveyor assembly. In some instances, the source of power will be mounted at one end or the other of the conveyor assembly. This mounting, although facilitating somewhat the provision of the drive between the motor and the auger, has the disadvantage of unbalancing the elevator, by making one end materially heavier than the other. The central or intermediate mounting of the motor on the mobile base or support has the advantage of positioning the motor where it will not affect the balance of the elevator, but such mounting has the disadvantage that it does not lend itself readily to the application of satisfactory drive connections to one end or the other of the auger. It is further found that the driving of the auger from one end or the other interferes with the functioning of the elevator in transferring material. If the drive is at the lower, material-receiving end, the ability of the elevator to pick up small grain and other material is adversely affected. The same may be said of a driving connection that puts power into the upper or material-discharge end of the auger. In either of these instances, the application of power to one end or the other of the auger results in considerable twisting or wrapping of the auger, thus requiring that the auger be made sufficiently strong to withstand what may be considered to be even normal deformation.

According to the present invention, all the advantages of a central motor mounting are utilized in conjunction with a novel drive mechanism whereby the auger or screw is driven from a point intermediate its ends, thus avoiding the use of long belts, shafts, and other external power-transmitting means. It is a principal object of the invention to provide a screw convey-

2

or assembly in which the housing or tube has an opening through the wall thereof through which access may be had for driving the auger from an external power source. A further object of the invention is to provide a novel housing assembly in which portions of the housing are provided as a pair of coaxial tubes arranged in end-to-end relationship with an enclosure structure serving to join the two tubular sections and in addition to substantially completely enclose drive mechanism for the auger. Another object of the invention is to provide a connector in the form of an enclosure as stated above and in addition to utilize a portion of the enclosure for the journaling of an intermediate or lay shaft for the driving mechanism.

The foregoing and other important objects and desirable features inherent in and encompassed by the invention will become apparent as a preferred embodiment of the invention is completely disclosed in the following detailed description and accompanying sheets of drawings in which:

Figure 1 is an end elevational view of the improved conveyor shown in the form of a portable small-grain elevator;

Figure 2 is a side elevational view, partly in section, as seen along the line 2—2—2—2 of Figure 1;

Figure 3 is an enlarged longitudinal sectional view of an intermediate portion of the screw conveyor assembly;

Figure 4 is a transverse sectional view taken substantially on the line 4—4 of Figure 3;

Figure 5 is a fragmentary sectional view as seen along the line 5—5 of Figure 4;

Figure 6 is an exploded view of major components involved in the assembly of the sections of the conveyor;

Figure 7 is an enlarged fragmentary sectional view, as seen along the line 7—7 of Figure 1, of part of the means for mounting the motor and for adjusting the conveyor tube on the mobile base;

Figure 8 is a fragmentary sectional view as seen along the line 8—8 of Figure 7;

Figure 9 is a face view of the improved drive wheel or sprocket; and

Figure 10 is a sectional view taken on the line 10—10 of Figure 9.

The elevator or screw conveyor assembly shown has a mobile base 10 comprising a transverse axle 11 and a pair of wheels 12. An upper supporting means 13 is carried by the axle 11 and, through the medium of means to be

presently described, carries at its upper end an upwardly inclined conveyor designated generally by the numeral 14.

The conveyor is in the form of a tubular housing made up of a plurality of coaxial tubes or tubular sections 15, 16, 17 and 18 (see Figure 3). The sections 15 and 16 have cooperating flanges 19 removably interconnected as by a plurality of bolts 20. The sections 17 and 18 are similarly interconnected, as by cooperating flanges 21 and bolts 22. The interconnection of the coaxial tubes 16 and 17 is effected by means that will be described below.

In normal use of the elevator, the wheels 12 are supported on the ground, as is the lower or material-receiving end of the conveyor assembly 14, as shown at 23 in Figures 1 and 2. The conveyor inclines upwardly to a material-discharge end designated generally by the numeral 24. The conveyor assembly is completed by a rotatable screw or auger indicated in its entirety by the numeral 25. The lower end 23 of the conveyor assembly is in the form of a cage having a bearing 26 for journaling the lower end of the auger or screw 25. The upper end 24 of the conveyor housing has a coaxial bearing 27 for journaling the upper end of the screw. According to the present invention, the screw 25 is made up of a pair of coaxial auger or screw sections 28 and 29 wound respectively on coaxial shafts 30 and 31 that have their inner terminal ends proximate and axially spaced apart as shown in Figure 3.

The coaxial tubular sections 16 and 17 have their proximate ends spaced apart axially as shown in Figure 3, to provide what may be termed a peripheral or circumferential slot 32 in the conveyor housing. This slot is radially aligned with the space between the proximate or inner ends of the shafts 30 and 31. This slot 32 is an important feature of the invention, because it accommodates the improved driving means for the auger or screw 25. The main components of the drive include a drive member in the form of a sprocket 33 having a hub 34 provided at opposite sides with shaft-receiving means 35 and 36 for respectively receiving the proximate ends of the screw shafts 30 and 31. The hub thus provides a coupling between the shafts 30 and 31 and the three elements 30, 31 and 33 are interconnected for rotation together by removable connecting pins 37 and 38.

The drive member or sprocket 33 has a circular body 39, the toothed periphery of which provides means for receiving drive from an external source, as will presently appear. The circular body 39 has opposite radial faces provided respectively with outwardly opening grooves 40 and 41. These grooves cooperate respectively with the circular edges of the proximate ends of the tube sections 16 and 17 to provide a material-tight seal (Figure 3). The outside diameter of the drive member or sprocket 33 is, as shown, larger than the outer diameter of the tubular housing made up of the sections 15, 16, 17 and 18. By this means, power may be applied to the auger 25 intermediate its ends rather than at either of its ends as heretofore known.

The tubes 16 and 17 are interconnected by a connector means designated generally by the numeral 42. This connector serves not only as means for completing the assembly of the conveyor 14 but also as means for mounting the conveyor on the upright supporting structure 13. Still further, the connector 42 serves to carry

and to enclose parts of the driving mechanism, particularly enclosing the sprocket for the drive wheel 33.

This connector comprises a pair of complementary sections 43 and 44 respectively having flanges 45 and 46 (Figures 4 and 6) which may be secured together as by a plurality of bolts 47 to embrace the coaxial tubes 16 and 17. As best shown in Figure 3, the connector section 43 has a pair of coaxially spaced semi-circular flanges 48 and 49 that respectively embrace the upper portions of the tubes 16 and 17. This section further includes an intermediate and integral housing portion 50 of larger diameter than that of the flanges 48 and 49. The portion 50 is made larger to accommodate the increase in diameter of the sprocket 33 over the tubes 16 and 17. The lower section 44 has coaxially spaced semi-circular flanges 51 and 52 that respectively embrace lower portions of the tubes 16 and 17 and thus complement the flanges 48 and 49 on the upper section 43. The lower section has a central or intermediate enlarged portion 53 which complements the enlarged central portion 50 of the upper section. The enlarged portion 53 of the lower section is cut out at 54 to provide an opening through which a portion of the sprocket 33 is visible. In other words, access may be had to the sprocket 33 through this opening.

The two sections 43 and 44 are assembled about the tubes 16 and 17, as suggested in Figure 6, to give an assembly as shown in Figure 4. Added to the assembly is means for supporting the connector 42 on the upright supporting structure 13. Part of this means comprises a casing or housing 55 having bearings 56 and 57 for journaling a transverse counter or lay shaft 58. The casing 55 includes an integral extension portion 59 provided with a bearing 60 for supporting one end of a short shaft 61 perpendicular to the transverse shaft 58. The other end portion of the shaft 61 is journaled in a second bearing 62 that is coaxial with the bearing 60 and that is formed in an integral wall 63 of the casing 55. A bevel pinion 64 is pinned to the end of the shaft 61 adjacent the bearing 62, and is in constant mesh with a bevel pinion 65 on the transverse shaft 58.

The lower section 44 of the connector means 42 is provided with a plurality of apertured depending ears 66 which, together with bolts 67 and ears 68 on the casing 55, mount the case rigidly on the connector 42.

Power is transmitted to the sprocket 33 and thus to the auger 25 by means of the shaft 61 through the medium of driving means including an external drive member in the form of a small sprocket 69 pinned or keyed to the shaft 61 intermediate its bearings 60 and 62. Power-transmitting means such as an endless flexible element or chain 70 interconnects or is trained about the sprockets 69 and 33. This chain operates substantially within the enclosure afforded by the intermediate and continuous portions 50 and 53 of the connector sections 43 and 44, the chain passing through the opening 54 in the lower section 44.

The structure just described is mounted on the upright support 13 by means comprising a pair of upright members 71 and 72 forming part of the upright support 13. The upper ends of the members 71 and 72 are formed respectively as bearings 73 and 74 to receive and journal opposite ends of the transverse shaft 58 (Figure 1). The bearings 73 and 74 are sufficiently large to

accommodate respectively intermediate bearings 75 and 76 formed at the upper ends of depending links 77 and 78 for a motor support having a horizontal base 79 on which is carried a source of power, here shown as an internal combustion engine 80. Details of the bearings 74 and 76 are shown in Figure 8. See also Figures 4 and 7.

The internal combustion engine 80 has a power output shaft 81 on which is keyed a sprocket 82. This sprocket is connected by a chain 83 to a 10 sprocket 84 keyed to the shaft 58 intermediate the bearing 73 and the casing 55. Although the elevator or screw conveyor assembly 14 is capable of being pivoted about the shaft 58, the relationship of the drive will not change, since the motor support 77-78-79 is concentric with the sprocket 84 about the shaft 58. Independent of its pivotal adjustment about the center at 58, the elevator assembly 14 is capable of being raised or lowered on the supporting structure 13. This result is accomplished by means of a crank 85 connected to a windlass 86 carried on the upright member 72. A cable 87 is wound on this windlass and passes upwardly and then downwardly about a sheave 88 at the upper end of the member 72. The cable passes thence about the sheave 89 on the bearing 74 and transversely across to a sheave 90 on the bearing 73 of the opposite upright member 71. The cable passes thence upwardly about a sheave 91 at the upper end of the member 71 and thence downwardly to an anchor point 92 on the bearing 73. The means for adjusting the elevator relative to the upright supporting structure 13 maintains the relative position of the screw conveyor 14 and the motor or internal combustion engine 80.

A further feature of the invention resides in the internal supporting of the proximate ends of the auger or screw shafts 30 and 31 from the connector means 42. The manner in which the bearings or supports are provided is best shown in Figures 3 and 6, wherein it will be seen that the upper section 43 of the connector 42 has a pair of axially spaced depending bearing hangers 93 and 94 which straddle the hub 34 of the sprocket 33. These hangers are preferably integrally formed with the flanges 48 and 49 on the connector section 43. The tubes 16 and 17 are respectively apertured at 95 and 96 to respectively receive the hangers 93 and 94 when the assembly is made. (See Figure 6.) As best shown in Figure 5, each of the bearing hangers has a section as illustrated, thus affording a shape which does not interfere with the material flow as material is propelled by the auger 25 from the end 23 to the end 24 of the screw conveyor assembly.

In this respect, it is a still further feature of the invention to provide material-impelling means on the sprocket 33. This means may take the form of one or more material-engaging elements or blades 97, each preferably in the form of the section of a spiral or helix. The auger sections 28 and 29 have the same directional spiral and preferably the same pitch. The same is true of the helical section means 97 on the sprocket 33. The sprocket is of spoked construction as shown in Figure 9 and the spokes, illustrated at 98, are formed as shown in Figure 10 to facilitate the flow of material. The sprocket thus is of open construction at its center.

The mounting of the screw conveyor assembly 14 on the mobile base 10 is completed by a pair of diagonal brace members 99, which is a construction that is generally conventional.

The assembly of the tubular sections and the connector 42 may proceed as follows: The two tubes 16 and 17 may be arranged as shown in Figure 3 with the sprocket 33 therebetween. The upper and lower sections of the connector 42 are then assembled. The auger sections 28 and 29 are introduced into the assembly from opposite directions and the auger shafts 30 and 31 are pinned at 37 and 38 to the hub 34 of the sprocket. Since the tubes 15 and 18 will not be in place, the person making the assembly may reach through the flanged ends of the tubes 16 and 17 to insert the pins 37 and 38. The tubes 15 and 18 are then assembled from opposite ends respectively and connected at 19-20 and 21-22. The casing 55 may then be assembled; or it may have been assembled previously, since it does not in any event interfere with the assembly of the sections 15 and 18. The entire assembly 14 may then be mounted on the upright structure 13, the motor support 77-78-79 having been previously mounted on the shaft 58, and the bearings 75 and 76 are respectively received by the bearings 73 and 74. The remaining components of the elevator are assembled and adjusted and the elevator is ready for use and operation.

Inasmuch as the drive is concentrated at the central portion of the conveyor assembly and is located above the wheels 12 of the mobile base 10, the balance of the elevator is not affected and conventional external complicated driving mechanisms are eliminated. The sprocket 33 affords no interference to the flow of material lengthwise of the assembly 14, since it is provided with the helical means 97. The bearing hangers 93 and 94, as previously stated, are formed to present as little as possible interference with material flow.

Other features and advantages of the invention not specifically enumerated herein will undoubtedly occur to those versed in the art, as likewise will numerous modifications and alterations in the preferred embodiment of the invention disclosed, all of which may be achieved without departing from the spirit and scope of the invention as defined in the appended claims.

What is claimed is:

1. A screw conveyor, comprising: a pair of tubes positioned in coaxial end-to-end relation with their proximate ends spaced apart, each tube having an opening through its wall adjacent its end that is proximate to the other tube; a pair of coaxial shaft means respectively within the tubes and having proximate ends generally radially aligned with the spaced ends of the tubes; a drive member having a circular body of larger diameter than at least one of the tubes and a hub having coaxial shaft-receiving means at opposite sides thereof, said member being positioned in the space between the ends of the tubes and concentrically therewith, the body of the member extending radially outwardly through said space and the proximate ends of the shaft means being received respectively in said shaft-receiving means of the hub; a connector outside the tube spanning the drive member and connected to the tubes for interconnecting the tubes; and said connector having a pair of supports thereon projecting respectively through the aforesaid openings in the tube and respectively journaling the shaft means.

2. The invention defined in claim 1, further characterized in that: each shaft carries a helical conveyor and the helices of the conveyors are

wound in the same direction; and each of the supports on the connector is shaped as a section as the conveyor helix to facilitate material flow past said support.
